[57] CLAIM

The ornamental design for stationery box, as shown and described.

DESCRIPTION

FIG. 1 is a perspective view of stationery box showing my new design;

FIG. 2 is a front elevational view thereof;

FIG. 3 is a rear elevational view thereof;

FIG. 4 is a left side elevational view thereof; with the right side being a mirror image of that shown;

FIG. 5 is a top side elevational view thereof; and

FIG. 6 is a bottom side elevational view thereof; and,

FIG. 7 is a perspective view of my design with the lid member in an opened condition, the elements depicted by means of broken lines being shown for illustrative purposes only and forming no part of the claimed design.
